UNITED STATES PATENT OFFICE.

CARL HOCHSTADT, PHILIPP WENZEL, AND HERMAN HEINEBACH, OF CHICAGO, ILLINOIS.

MOLD FOR CASTING TYPE.

SPECIFICATION forming part of Letters Patent No. 352,869, dated November 16, 1886.

Application filed April 9, 1884. Serial No. 127,105. (No model.)

To all whom it may concern:

Be it known that we, CARL HOCHSTADT, PHILIPP WENZEL, and HERMAN HEINEBACH, of Chicago, county of Cook, and State of Illinois, have invented certain new and useful Improvements in Molds for Casting Type, of which the following is a full, clear, and exact description, that will enable others to make and use the same, reference being had to the accompanying drawings, forming a part of this specification.

The object of this improvement is to provide means for breaking off the "jets" from the body of the type before the same are discharged from the molds, the jets being thrown into one receptacle and the type into another, thus entirely obviating the necessity of doing this work by hand.

Figure 1 is a front view of the jaws in which the mold-blocks are placed; Fig. 2, a view of the opposite or back side; Fig. 3, a side elevation showing parts omitted in Figs. 1 and 2. Figs. 4, 5, 6, 7, and 8 are different sectional views of the mold-blocks, and Figs. 9 and 10 are views of the type and jet.

Most of the mechanism is necessarily shown in the drawings, in order to fully bring out the improvement. The description will therefore be confined to the improved features and the parts to which they are attached.

Referring to the drawings, A A' represent the jaws to which the mold-blocks B B' are secured, Fig. 2 having parts broken away, showing the manner of rigidly securing the mold-blocks, which feature is common to this class of machines. The upper jaw, A, to which the upper half, B, of the mold is attached, opens upward on a pivot to the position indicated by the dotted lines in Fig. 2, while the under jaw, carrying the lower half, B', of the mold, remains in a stationary position, the upper jaw being raised at the proper time to allow the type and jet to drop out of the molds.

The molds and parts to which they are attached being set at about the angle indicated in Figs. 1 and 2, the type naturally drops out of the molds when the jaws separate, and gravitates into the receptacle provided to receive it.

Fig. 4 is a vertical central longitudinal section of the mold-blocks, showing the back side

of the mold-chamber a, Fig. 5 showing the opposite side of the same.

Fig. 6 shows the type-body a' and the jet a² in position as they are cast in the molds, the jet being of a wedge shape, and attached by a small surface to the foot of the type-body.

Fig. 7 is a vertical transverse section of the mold-blocks in the plane 7 7, Fig. 4, and shows the pin b, which passes through from the outside of the bottom half of the mold-block and projects a little way into the chamber of the mold, so that in the process of casting the type the surplus metal forming the jet will be held in place and broken off from the foot of the type-body when the upper mold block is raised to discharge the type.

Fig. 8 is a vertical longitudinal section in the plane 8 8, Fig. 5, showing the pin b' recessed in the upper half of the mold, the outer end just projecting into the chamber a, in order to have sufficient hold of the type to raise it out of the mold, when it drops onto the slide D and is carried away. The projecting end of this pin b' is placed so as to have contact with the type near the foot and at the junction with the jet. A companion pin, b², is placed in the upper half of the mold, and has a bearing near the face end of the type. When the upper half of the mold rises up, these pins break or separate the type from the jet, the type dropping out as the mold opens, the jet being temporarily retained in the lower member of the mold by the pin b, (or its equivalent means,) and is dislodged or ejected therefrom by means of the curved arm D' coming in contact with that portion of the jet projecting from the mold, the jet dropping into the funnel-shaped receptacle d, (see Fig. 3,) and is entirely separated from the type.

The curved arm D' is adjustably secured to the upper half or member of the mold and receives the required motion therefrom, the dotted lines indicating the opposite position of the jet-ejecting arm when the mold is wide open. The end of the ejecting-arm having contact with the jet is beveled, as shown at d', Fig. 2, whereby the jet is wedged away from the mold in a direction different from that of the curve described by the jet-ejecting arm. In this case the jet-ejecting arm is attached to the upper member of the mold; but it is obvious that

the arm may be connected to any part of the mold or machine whereby the required motion is imparted to the same, and the jet automatically ejected after being broken from the type.

5 The ejecting-arm is adapted to move in close proximity past the jet end of the mold and eject the jet when the mold is open.

Figs. 9 and 10 show opposite sides of the type-body and jet broken apart, the bearing-10 marks of the pins being indicated. By this arrangement the type and jet are automatically broken apart by the opening of the mold, and automatically discharged into receptacles entirely separate from each other, thus saving 15 much valuable time and labor in the process of casting type.

Having thus described our invention, what we claim as new, and desire to secure by Letters Patent, is—

20 1. In a type-casting machine, the combination, with the lower stationary member of the mold, having a detaining device in the jet-casting portion, of the upper mold-section, provided with similar detaining devices in 25 the type-casting portion, substantially as described.

2. In a type-casting machine, the combination, with the lower or stationary half of the mold B', of the pin b, the upper movable half 30 of the mold B, and the pins b' b², whereby the jet is broken from the type in the process of casting, substantially as described.

3. In a type-casting machine, the combination, with the type-mold, the upper member 35 of which is provided with a type-detainer, and the lower member of which is provided with a

jet-retainer, of a jet-discharging arm connected with a moving part of the machine and moving in close proximity with the jet end of the mold, substantially as described.

40

4. In combination, substantially as set forth, the mold having in one member a type-detainer, and in the other or companion member a jet-detainer, and a jet-ejecting arm moving past the jet end of the mold while the mold is 45 open, whereby the type and jet are automatically broken apart when the mold opens, and the jet ejected therefrom.

45

5. In combination, substantially as set forth, the mold having a jet-detainer in one member, and a jet-discharging arm on the other member, provided with a beveled end engaging the projecting portion of the jet to wedge it off from the mold and eject it therefrom when the mold opens.

50

6. In a type-casting machine, the combination of the mold and a jet-discharging arm attached to and receiving motion from a moving part of said machine, substantially as described.

60

7. In a type-casting machine, the combination, with the upper and lower parts forming the mold, of the pins b b' b² and the curved arm D, adjustably secured in relation to said mold and adapted to move therewith, substantially as and for the purpose set forth.
